(57)

CLAIM

I claim the ornamental design for a blade, as shown and described.

DESCRIPTION

FIG. 1 is a perspective view showing my new design.
 FIG. 2 is a side elevational view thereof, the opposite side elevational view being a mirror image thereof;
 FIG. 3 is a top plan view thereof;
 FIG. 4 is a bottom plan view thereof;
 FIG. 5 is a front elevational view thereof; and,
 FIG. 6 is a rear elevational view thereof.
